RUG CUSHION OR SIMILAR ARTICLE

Dixon R. Harwin, Los Angeles, Virgil H. Bodle, Temple City, and Lothar Strauss, Los Angeles, Calif., assignors to National Sponge Cushion Co., Inc., Los Angeles, Calif., a corporation of California

Application July 2, 1956, Serial No. 42,112

Term of patent 14 years

(Cl. D92—4)

Fig. 1.

Fig. 2.

Fig. 3.

Fig. 1 is a plan view of a rug cushion or similar article, showing our new design.

Figs. 2 and 3 are enlarged profile views taken, respectively, along the side and lower edges of the cushion.

The dominant features of the design reside in the portions shown in full lines.

We claim:

The ornamental design for a rug cushion or similar article, substantially as shown and described.
